J. PETZ

POCKET CIGARETTE ROLLING DEVICE

Filed June 9, 1923

Patented May 5, 1925.

1,536,923

UNITED STATES PATENT OFFICE.

JOHAN PETZ, OF MONTERREY, MEXICO.

POCKET CIGARETTE-ROLLING DEVICE.

Application filed June 9, 1923. Serial No. 644,466.

To all whom it may concern:

Be it known that I, JOHAN PETZ, a citizen of the Republic of Mexico, residing at Monterrey, in the State of Nuevo Leon and 5 Republic of Mexico, have invented certain new and useful Improvements in Pocket Cigarette-Rolling Devices, of which the following is a specification.

This invention has general reference to 10 smokers' accessories, having more particular reference to a cigarette rolling device which is combined as a unitary article with the container for holding the tobacco and paper.

The invention has for an object to provide 15 a novel and simple device of this sort, of a size to be conveniently carried in the pocket of the user.

For further comprehension of the invention, and of the objects and advantages 20 thereof, reference will be had to the following description and accompanying drawings, and to the appended claims in which the various novel features of the invention are more particularly set forth.

25 Fig. 1 of the drawings is a face view, with parts in longitudinal section, of my improved device.

Fig. 2 is a transverse sectional view thereof, this view being taken on the line 2—2 30 of Fig. 3, with additional parts broken away.

Fig. 3 is a sectional view at right angles to Fig. 2 and taken on the line 3—3 of the latter figure.

35 Fig. 4 is a detail elevational view showing the means for curling the edge of the paper over the tobacco in the pocket.

Fig. 5 is a transverse vertical section on the line 5—5 of Fig. 4.

40 My improved device as here shown comprises a flat substantially rectangular casing which may be slightly rounded at the corners as shown and which comprises a body 10 to which is hinged along one side, as at 11 a flanged cover 12 of equal area, an ordinary type of catch 13 being provided on the opposite side to hold the cover closed. The body member 10 is provided also with a second interior cover 15 which 45 is located under the cover 12 and hinged in the casing as at 16 at the side of the latter opposite to the hinge 11, a lip 18 being provided on the side of the casing adjacent such hinge to support the free edge of the 50 said cover 15. This lip is here shown as formed on an interior member 20 extend-

ing around the casing and to which the cover 15 is hinged, the cover 15 and member 20 enclosing a compartment 21 adapted to contain the tobacco, and may also contain the cigarette papers, as indicated at P in Fig. 3. At the ends of the compartment 21 the top parts of the member 20 are offset from the main walls of the casing at their upper ends, leaving spaces in which are accommodated a pair of arms 25 pivoted at one end as at 26 to the said main walls of the casing at points slightly nearer to the side of the casing to which the cover 12 is hinged than to the opposite side.

Extending between, and journaled in, the free ends of these arms 25 is a roller 27 having fixed to the ends of its trunnions a pair of sliding discs 28 which are localized in guides formed partly by the main panel of the cover 12 and partly by flanges 29 projected inwardly from the end walls of the same. Secured to the cover 12 as at 30 near the hinged side thereof, is one end of a 55 flexible apron 31 made of cloth or other suitable material and which extends toward the opposite side of the cover, passing first along the outer face of the cover, then inwardly through a slot 32 extending substantially the length of the latter, around the roller 27 and finally outward through a second longitudinal slot 33 in the cover to be secured to the latter as at 34.

In the use of the device in rolling cigarettes the cover 12 is thrown open, the arms 25 being swung outward as the cover opens and, by reason of the arms swinging on a different centre than the said cover, the roller 27 is moved to a point near the hinge side of the cover and adjacent the opening 32 in the latter, a degree of slack being thus left in the apron 31. This slack portion is pushed by the fingers through the slotted opening 32, forming a pocket to receive the tobacco. The inside cover 15 is then swung back and the necessary tobacco and paper removed from the compartment 21. The required amount of tobacco is inserted in the pocket in the apron, being suitably distributed along the latter, and the edge of the paper is inserted into the pocket, the paper being indicated in this position at p in Fig. 2, the opposite edge of the paper being moistened. The cover 12 100 is then closed, and as the roller 27 moves along the cover from one side toward the 105

other during this closing movement the pocket in the apron is pulled inward through the slot 32 and follows the said roller toward the slot 33. As will be understood there will be a rolling action imparted to the tobacco during this movement with a result of rolling the paper around the latter. When the roller passes the slot 33 to come to the position shown in full lines in Fig. 2 the apron 31 is stretched, and in consequence the finished cigarette is ejected through the said slot.

As shown in detail in Figs. 4 and 5 I provide a pair of short arms 40 which are formed with longitudinal slots 41 which are engaged with the trunnions of the roller 27, these arms carrying an arcuate cross-piece 42 at their outer ends which is provided at one side with finger extensions 43. In the use of the device as thus arranged the arms 40 are swung downward to place the cross-piece over the tobacco in the pocket in the apron, the fingers 41 projecting through slots 44 of suitable length in the apron 31, the arms 40 holding the cross-piece in this position with sufficient force, by frictional engagement with the arms 25, to cause the edge of the paper to be curled backward over the tobacco as indicated, the cross-piece 42 being then moved away and the operation continued as above set forth.

Having thus described my invention, what I claim as new and desire to protect by Letters Patent of the United States is as follows:

1. A device of the class described comprising a casing, a cover hinged thereto and formed with a pair of slots one near the hinged side and one near the opposite side, a roller adapted to pass from side to side of the cover as the latter swings between open and closed positions, a pair of arms hinged to the casing and having the said roller attached to their free ends, an apron secured at opposite ends to the said cover adjacent the respective slots in the latter, said apron having a degree of slack therein

when the cover is open whereby it may be partially projected through the first mentioned slot to receive the tobacco, and a removable member adapted to be inserted into the said pocket over the said tobacco to form a guide for the cigarette paper, said member being mounted on the free ends of the said arms. 55

2. A device of the class described comprising a casing, a cover hinged thereto and formed with a pair of slots one near the hinged side and one near the opposite side, a roller adapted to pass from side to side of the cover as the latter swings between open and closed positions, an apron secured at opposite ends to the said cover adjacent the respective slots in the latter, said apron having a degree of slack therein 60 when the cover is open whereby it may be partially projected through the first mentioned slot to receive the tobacco, and a removable member adapted to be inserted into the said pocket over the said tobacco to 65 form a guide for the cigarette paper.

3. A device of the class described comprising a casing, a cover hinged thereto and formed with a pair of slots one near the hinged side and one near the opposite side, a roller adapted to pass from side to side of the cover as the latter swings between open and closed positions, an apron secured at opposite ends to the said cover adjacent the respective slots in the latter, said apron having a degree of slack therein 70 when the cover is open whereby it may be partially projected through the first mentioned slot to receive the tobacco, and a removable member adapted to be inserted into the said pocket over the said tobacco to 75 form a guide for the cigarette paper.

In testimony whereof I have affixed my signature.

JOHAN PETZ.
